US00D775435S

(12) **United States Design Patent** (10) **Patent No.:** **US D775,435 S**
Risser et al. (45) **Date of Patent:** **** Dec. 27, 2016**

(54) **FEEDER**

- (71) Applicant: **Valco Companies, Inc.**, New Holland, PA (US)
- (72) Inventors: **Philip E. Risser**, Leola, PA (US); **Daniel B. Truong**, Lancaster, PA (US)
- (73) Assignee: **Valco Companies, Inc.**, New Holland, PA (US)
- (**) Term: **14 Years**
- (21) Appl. No.: **29/516,162**
- (22) Filed: **Jan. 29, 2015**

Related U.S. Application Data

- (63) Continuation-in-part of application No. 29/453,418, filed on Apr. 29, 2013, now abandoned.

CLAIM

The ornamental design for feeder, as shown and described.

DESCRIPTION

FIG. 1 is a perspective view of the feeder;
 FIG. 2 is a top view of the feeder;
 FIG. 3 is a bottom view of the feeder;
 FIG. 4 is a right side view of the feeder, the left side view being a mirror image thereof; and,
 FIG. 5 is a front view of the feeder, the back view being a mirror image thereof.

(Continued)

Broken lines and unshaded portions contained within broken lines, depict portions of the feeder that form no part of the claimed design. Dot-dash lines depict boundaries of claimed portions of the design.

1 Claim, 3 Drawing Sheets
